VIBRATION TRANSLATING DEVICE

George R. Yenzer, Queens Village, N. Y., assignor
to Bell Telephone Laboratories, Incorporated,
New York, N. Y., a corporation of New York

Application August 26, 1942, Serial No. 456,224

5 Claims. (Cl. 179—100.41)

This invention relates to vibration translating devices and the object of the invention is an improved translating device of the type in which the moving element is adapted to vibrate in a plurality of modes.

According to the general features of the invention the device has a single vibratory element such as a coil mounted between pole-pieces for vibration either torsionally or along its axis and a permanent magnet movable to either of two positions with respect to the pole-pieces to set up a flux which is either radial or transverse with respect to the coil. This structure is particularly useful as a phonograph reproducer (or recorder) since with a stylus connected to the coil the device will reproduce (or record) either hill and dale or lateral type records merely by moving the magnet to the proper position and without any change in the electrical circuit.

The invention will be more clearly understood from the following detail description and the accompanying drawing in which:

Fig. 1 is a perspective view of a reproducer according to the invention;

Figs. 2 and 3 are side views showing the magnet in its two positions; and

Fig. 4 is a front view showing particularly the pole-piece construction.

In the drawing, the signal coil 11 and its supporting structure is of the general type shown in Patent 2,027,169 to Harrison except that in this case the coil is supported entirely by a single flat spring member 12 secured to the bottom piece 13 of the casing 14. The member 12 tapers toward the coil support 15 both of which may be of any suitable light weight non-magnetic metal or this vibrating structure including the stiffening fin 16 may be molded in a single piece from suitable thermoplastic or thermosetting material. In any case the stylus 17 is preferably of the permanent type cemented into a socket in the support 15.

As in the case of the vibratory structure shown in the Harrison patent the spring member 12 is free to vibrate vertically when used with hill-and-dale records and torsionally when used with lateral cut records.

The coil is mounted in an annular air-gap defined by the lateral pole-pieces 18 and 19 and the central pole-piece 20, the latter being held in position by the non-magnetic member 21. The pole-piece 18 extends backwardly and terminates in an L-shaped piece 22 which engages the permanent magnet 23 as shown in Fig. 1. The pole-piece 19 is U-shaped at its front end the upper

arm 24 of which engages the magnet when the latter is in its upper position as shown in Figs. 1 and 2. This pole-piece also extends backwardly to an L-shaped portion 25 against which the magnet rests in its lower position as shown more clearly in Fig. 3.

With the magnet in its upper position the flux path extends from the north pole of the magnet through the U-shaped portion of the pole-piece 19, one side of the air-gap, the central pole-piece 20, the other side of the air-gap to the pole-piece 18 and the south pole of the magnet. This flux is transverse with respect to the coil 11 and under this condition the device will reproduce (or record) lateral cut records.

When the magnet is moved downwardly to the position of Fig. 3, the north pole is transferred from the arm 24 to the central pole-piece 20 and the south pole slides along the face of the arm 22 of the pole-piece 18 and makes contact with the arm 25 of the pole-piece 19. Under this condition the flux enters the pole-piece 20 and divides flowing radially across both sides of the gap to pole-pieces 18 and 19 and back to the south pole by way of the arms 22 and 25. With this radial flux the device will record or reproduce hill-and-dale or vertical cut records.

For convenience the magnet is fitted with a handle 26 or some equivalent means extending through the casing so that the device may be readily conditioned for operation in either mode. While the magnet by its own attraction will remain in either position under ordinary conditions the handle 26 may be provided with a spring catch 27 and any other known form of detent or locking device for maintaining the magnet in the position in which it is set. It will also be understood that in practice suitable means would be provided for guiding the magnet in its motion from one position to the other. These guides can be of any suitable non-magnetic material secured to the pole-pieces or secured to or formed integrally with the top or bottom plate of the casing. The leads (not shown) from the coil 11 may be connected to pins 28, 29 in the casing and these pins may serve both as the electrical connectors to the external circuit and the mechanical means for attaching the device to a suitable arm.

While the invention has been described with particular reference to a phonograph reproducer or recorder it will be understood that it is equally applicable to any electromagnetic device in which it is desired to produce either a radial or a trans-

verse flux and that various modifications of the structure illustrated may be made within the scope of the following claims.

What is claimed is:

1. In a vibration translating device the combination with a signal coil and pole-pieces defining a gap for the coil, of a permanent magnet adapted to be moved between the pole-pieces to set up either a radial or a transverse flux in the gap.
2. In a vibration translating device the combination with a pair of lateral pole-pieces and a central pole-piece defining an air-gap and a signal coil mounted for vibration in the gap, of a permanent magnet and extension members on the pole-pieces for selectively contacting the magnet to reverse the direction of the flux between the central and one of the lateral pole-pieces.
3. A device according to claim 1 in combination with a casing therefor and means externally of the casing for moving the magnet within the casing.
4. In a vibration translating device a pair of lateral pole-pieces and a central pole-piece defin-

ing an air-gap, a signal coil mounted for vibration in the gap and means for setting up a transverse or a radial flux in the gap comprising a movable permanent magnet having one pole

5. adapted to be moved from one of the lateral pole-pieces to the central pole-piece and another pole adapted to maintain contact with the other lateral pole-piece and move into contact with said one lateral pole-piece.
10. 5. A selectively universal phonograph reproducer comprising a pair of lateral pole-pieces and a central pole-piece defining an air-gap, a stylus, a signal coil attached thereto, a vertically and torsionally resilient spring member supporting the coil for vibration in the gap and means for producing either a radial or a transverse flux in the gap comprising extension members on the lateral pole-pieces, a permanent magnet cooperating with the pole-pieces and means for moving the
15. magnet between the extension members to reverse the direction of flux in one of the lateral pole-pieces.
